UNITED STATES PATENT OFFICE.

ADAM WINFIELD HANIGAN, OF PHILADELPHIA, PENNSYLVANIA, ASSIGNOR TO THE
ONTARIO TYPE MACHINE COMPANY, LIMITED, OF TORONTO, CANADA, A CORPORATION
OF ONTARIO.

PRINTER'S TYPE.

No. 896,381.

Specification of Letters Patent. Patented Aug. 18, 1908.

Application filed April 10, 1906. Serial No. 310,964. Renewed June 23, 1908. Serial No. 440,034.

To all whom it may concern:

Be it known that I, ADAM WINFIELD HANIGAN, of the city of Philadelphia, in the county of Philadelphia and State of Pennsylvania, one of the United States of America, have invented certain new and useful Improvements in Printers' Type; and I hereby declare that the following is a full, clear, and exact description of the same.

10. This invention relates to printers' type which can be produced in individual and sequential order, assembled into selective groups, justified, and then securely locked in their assembled and justified condition, as 15 hereinafter described and specifically pointed out in the appended claims.

For a full understanding of the invention reference is to be had to the following description and to the accompanying drawings.

20. in which,

Figure 1 is a perspective view of a part of a composed line of printers' type, showing two groups of type assembled, justified and locked in their assembled and justified condition. Fig. 2 is a side elevation of the same. Fig. 3 is an end view of the same. Fig. 4 is a perspective view of one of the type. Fig. 5 is a perspective view of the locking piece. Fig. 6 is a side elevation showing the position 30. of the locking piece preparatory to being impressed into the locking grooves of the type. Fig. 7 is a perspective view looking at the inner side of the locking piece after having been impressed into the locking grooves of a justified line of type with two types connected thereto.

Like letters of reference refer to like parts throughout the specification and drawings.

a represents one of the type in which is 40 formed a transverse groove *b* intermediate the ends of the type and of a substantially dove tail shape. The types *a* are cast in individual and sequential order and then assembled into selective groups with the transverse grooves *b* alined. When the line of types which may be of any selected length, is composed and justified, a locking piece *c* is 45 impressed into the alined grooves *b* to lock the types *a* in their composed and justified condition. The side edges *f* of the locking piece are beveled to correspond with the angle of convergence of the sides of the dove tail grooves to insure a perfect contact therewith. The locking piece is curved as shown 50 in Figs. 5 and 6 to bring its beveled edges 55

into a smaller compass than the distance between the edges of the dove tail grooves to facilitate its entry therein. In assembling the locking piece and the types, the former is placed in the grooves as shown in Fig. 6, and when so placed is subjected to the action of a pressing means which will when exerting its force upon it press it into the grooves *b* and against the adjacent faces of the types. The pressure exerted on the locking piece squeezes 65 it into the spaces between the groups of type and forms protuberances *e* on its inner face to hold them in their word spaced condition. The locking piece *c* is preferably made of pliable metal of a non brittle character and 70 corrugated lengthwise as shown in Figs. 5 and 6.

The formation of the grooves *b* and the engagement therewith of the edges *f* of the locking piece when impressed therein prevent 75 the lateral or accidental removal of the types from the line of type and the protuberances or spacers *e* prevent any deviation of the types from their justified position. By forming the locking piece with longitudinal corrugations, the rigidity of the locking piece is intensified without detracting from the pliability of the metal of which the locking strip is made.

The types have been shown and described 85 to be provided with grooves *b* of a dove tail formation, but it is not desired to confine the invention to this particular style of groove as other grooves suitable for the purpose will answer equally as well, nor is it desired to 90 confine the invention to any particular method of casting the types, assembling them, justifying them and impressing the locking piece into the type grooves and spaces.

As shown in Fig. 1, the pressing means exerts its greatest pressure upon the locking piece contiguous to its side edges *f* so that the spacing protuberances *e* will project into the spaces between the groups of types from the inner face of the locking piece at or contiguous to its side edges *f* as shown in Fig. 3, to hold the type groups in their spaced condition and maintain the justification of the line.

Having thus fully described my invention 105 what I claim as new and desire to secure by Letters Patent is:

1. A line of type or type bar comprising an assembled group or series of groups of word spaced and justified printers' type with 110

alined grooves in one surface thereof, and a locking strip contained in said grooves having word spacers adjacent to its top and bottom edges and protruding from its inner face into the spaces between the groups of type to hold them in their word spaced and justified condition.

2. A line of type or type bar comprising an assembled group or series of groups of word spaced and justified printers' type with alined grooves in one surface thereof, and a locking

strip contained in said grooves having word spacers protruding from its inner face into the spaces between the assembled groups, but not filling the said spaces lengthwise of 15 the type, to hold the assembled groups in their word spaced and justified condition.

Philadelphia, March 7th, 1906.

ADAM WINFIELD HANIGAN

Signed in the presence of—

CHAS. H. DOUGHERTY,
JOHN A. MIMS.
